UNITED STATES PATENT OFFICE.

HERBERT H. ICE, OF MUSKOGEE, OKLAHOMA.

DUPLEX OIL-WELL PUMPING POWER.

Application filed July 3, 1926. Serial No. 120,348.

This invention relates to a duplex oil well pumping power apparatus.

This power or mechanism is preferably called "the duplex oil well pumping power", because, as the name applies, it is practically two powers in one; this principle being very advantageous for pumping or operating a group of wells of different nature; for example, small or head wells will not permit 10 of fast motion pumping without injuring such wells, while large producing oil wells with considerable salt water do require fast and sturdy motion pumping.

One of the objects of my invention is to 15 relieve the operator of the necessity of buying engines for the operation or pumping of individual wells.

Another object of my invention is to design a pumping apparatus suitable for the 20 proper pumping of a reasonable number of wells of different nature, all from one source of power.

This apparatus is a decided improvement over my former apparatus shown in my 25 United States Patents Number 859,451 and Number 1,288,008.

With the foregoing and other objects in view, my invention comprises certain novel constructions, combinations, and arrangements of parts as will be hereinafter fully 30 described, illustrated in the accompanying drawings, and more particularly pointed out in the appended claims.

In the drawings:

Figure 1 is a vertical, central sectional view of an apparatus constructed in accordance with the present invention.

Figure 2 is a fragmentary, vertical, central sectional view of an apparatus constructed in accordance with the present invention, at substantially right angles to the line on which Figure 1 is taken, and showing the eccentrics in an extended position, whereas in Figure 1, the eccentrics are shown 45 in what might be termed a "neutral" position.

Figure 3 is a sectional view taken on line 3-3, Figure 2, and looking in the direction of the arrows.

Figure 4 is an enlarged fragmentary plan view of the belt wheel.

Figure 5 is a plan view of the belt wheel and the stay eye bolts for bracing the main shaft.

Figure 6 is a sectional view taken on line 6-6, Figure 2 and looking in the direction of the arrows.

Figure 7 is an enlarged fragmentary inside view of the belt wheel showing the manner of connecting the sections of the rim 60 and the means for fastening the outer ends of the spokes, while

Figure 8 is an edge view of the same.

Figure 9 is an enlarged fragmentary view 65 of the outside of the rim of the belt wheel.

Figure 10 is an enlarged top plan view 70 of the connecting device for the eye bolt, pipe support and anchor stay rod, shown also in Figure 1.

Referring to the drawings by numerals, 1 75 is the foundation, preferably formed of concrete or cement, and 2 designates the floor line (Figs. 1 and 2). Supported upon the foundation 1 is the primary casting 3. This casting 3 is provided with a depending hub 4 against the lower end of which is circular threaded plate 5. A base plate 6 is positioned against plate 5, and by means of screw-like bolts 7, the plates 6 and 5 are held against the hub 4, prior to seating the casting 3 on the foundation 1. By means 80 of anchor bolts 8, the casting is securely fastened upon the foundation 1.

The stationary shaft 9 is threaded at its 85 lower end into plate 5, and upon this shaft 9 are positioned two pressed in bronze bushings 10. Surrounding shaft 9 is a bronze ring plate 11, which rests upon the flanged upper portion 12 of the hub 4. A drive 90 sleeve 13 is positioned upon shaft 9, with the bushing 10 therebetween, and mounted upon this sleeve 13 is the belt wheel 14, high speed eccentric 15 and low speed eccentric 16. I use the term "high speed" with reference 95 to the eccentric 15 because it is keyed upon sleeve 13 and works at a greater speed than the "low speed" eccentric 16, as eccentric 16 is geared to sleeve 13, so that it will approximately work at about two-thirds the speed of eccentric 15.

An auxiliary adjustable casting 17 is mounted in the primary casting 3, and I use the term "casting" in a generic sense, because these castings 3 and 17 might be termed casings or containers. The casting 17 is provided with a gear receiving groove 18 in which is positioned ring-like gear 19; gear 19 being provided with internal teeth clearly 100 105

shown in Figure 6. This gear 19 meshes with the pinion 20, the hub 21 (dotted lines) of which is hexagonal in shape at its bottom end. A ring plate 22 rests upon the upper flanged edge of gear 19 (Fig. 2), and a ring 23 is drawn or tightly held between the depending flange on the outer edge of ring plate 22 and the outer flanged edge of gear 19 by means of screw bolts 24, so that the ring plate 22 is locked or fastened tightly upon the upper edge of the primary gear 19. A cover plate 25 is fastened by screw bolts 26 upon the casting 17; this cover plate 25 keeps foreign substances such as dirt, dust, and the like from entering the space between the gears, and as the gears preferably work in oil, it clearly assists in keeping the oil clean too. An upstanding integral roller lug 27 is formed on the ring plate 22 (Fig. 2), and mounted upon the roller lug is a tire-like sleeve 28; a ball bearing device 29 is mounted upon the upper end of roller lug 27, which roller lug and sleeve 28 extends into the auxiliary or low speed eccentric 16. A cover plate 30 is over the ball bearing device 29 and roller lug 27, closing the upper end of the opening 31 in the eccentric 16. The eccentric rings 34 and 36 are alike and each is provided with suitable pump rod connections 32. The eccentric hub 16 is bronze bushed and rests in the upper end of the pinion 20. This eccentric 16 comprises the inner rotatable section 33, loosely mounted upon drive sleeve 13, and outer reciprocal section 34. Therefore, it will be seen that when the belt wheel 14 is rotated, sleeve 13 will be rotated, resulting in pinion 20 being rotated, which in turn will rotate gear 19, and through the roller lug 27, the inner section 31, of eccentric 16 will be rotated slowly, and the outer section 34 will be slowly reciprocated for operating slowly the pumps of certain oil wells.

The primary or "high speed" eccentric 15 comprises inner rotatable section 35 and the outer reciprocal section 36. It is to be noted that the central portion of drive sleeve 13 tapers and that the eccentric 15 and belt wheel 14 are mounted on this tapered portion (Figs. 1 and 2). The eccentric 15 is held tightly upon the tapered portion of sleeve 13 by means of bolts 37, which bolts pass through portions of the hub 38 of the belt wheel 14 and through the hub 39 of the inner rotatable section 35 of said eccentric 15. It will be seen that I have provided means for drawing up the eccentric 15, tightly upon the tapered drive sleeve, towards the belt wheel 14.

The hub 38 of the belt wheel 14 is also drawn upon the tapered portion of the sleeve 13 by means of screw bolts 40, which bolts extend through clamp ring 41, on sleeve 13, into the hub 38 of said belt wheel 14. A "let in" split ring 42 is positioned between

said clamp ring 41 and drive sleeve 13, fastening these elements together against independent movement. It is to be understood that power is supplied to the belt wheel 14 and by reason of said belt wheel and eccentric 15 being keyed at 43 upon the drive sleeve 13, these two elements will be rotated at the same speed, which is much greater than the slow movement of the auxiliary eccentric 16.

The belt wheel 14 includes the hub 38 integral with hub plate 44 (Fig. 4) and fastened on said plate 44, by U-shaped bolts 45, are spokes 46. The rim 47 is preferably made in sections (Figs. 7 to 9) and the abutting ends of these sections are held together by plates 48. A ring 49, substantially H-shaped in cross section, is fastened within the rim, against plates 48 (Figs. 7 and 8), and a plate 50 is placed over and extending in the outer end of each spoke 46, and eye-bolts 51 extend through plates 50 and part of the ring 49, and a bolt 52 extends through each spoke and the eyes of bolts 51, whereby the outer ends of said spokes are securely fastened in position upon ring 49 and rim 47. Brace rods 53 have their outer ends fastened to ring 49 and their inner ends are fastened to the lower end of hub 38. Upper brace rods 54 are fastened at their outer ends to ring 49, and their inner ends are fastened to a ring or annular plate 55 mounted on the upper or outer end of drive sleeve 13.

The outer end of shaft 9 is suitably formed for receiving a tool such as a wrench for assisting in setting or placing the shaft, with respect to its being screwed into threaded plate 5. Stay eye bolts or rods 56 have their eyes 57 over the outer end of shaft 9, and the outer ends of these rods are fastened through a block 58 (Figs. 1 and 10). Block 58 is socketed for receiving the tenon-like upper end 59 of pipe support 60. A pair of plates 61 is pivotally mounted at one end on rounded ends of block 58, and carried by the other or lower end of plates 61 is a second block or sleeve 63, through which extends the anchor stay rod 64; this block 63 being retained in position upon plates 61 by means of rounded ends 65 of block 63. The pipe support 60 can be secured in any suitable manner upon the ground or to a foundation (not shown). It is obvious that each stay rod 56 is provided with one of these supporting and bracing devices, comprising said plates 61, blocks and pipe support 60 and stay rod 64.

It is to be understood that said primary casting 3 has a dropped and bracketed hub, taper-bored off center, sufficient to permit gear tooth adjustment by turning casting 17 and locking the same in the desired position, for the proper gear mesh through the medium of the screw bolts 66 (Fig. 2).

This structure provides a positive and most simple adjustment possible and easy of access. The way I have shown and described shaft 9 illustrates a structure which is most substantial and convenient as it is self centering and permits installing or removing said shaft at any time desired, without disturbing any inside parts. A further advantage of this structure is that it permits true alignment of shaft 9 with respect to the primary casting 3 and assures long and efficient service.

It is to be understood that the gear groove 18 is what might be called an eccentrically located bearing for the driven gear 19. Both gears 19 and 20 operate in a bath of oil; these gears have wide faces and helical teeth which permit perfect and easy running, free from backlash.

20 The ball bearing device 29 rolls in and out on the under face of plate 30 (Fig. 2), its purpose being to carry a part of the weight of eccentric 16.

This "two motion power" is made possible and practical by the gearing, controlling the movement of eccentric 16 and the primary eccentric operated directly by the drive sleeve 13.

It is to be understood that I am making no specific claim to any type of means for connecting my eccentrics to well pumps, and I have only designated the pump connections broadly by the numeral 32, my invention being primarily directed to the construction or "hook-up" of the two eccentrics and the belt wheel.

While I have described the preferred embodiment of my invention and illustrated the same in the accompanying drawings, certain minor changes or alterations may appear to one skilled in the art to which this invention relates during the extensive manufacture of the same, and, I, therefore, reserve the right to make such alterations or changes as shall fairly fall within the scope of the appended claims.

What I claim is:

1. In an apparatus of the class described, the combination of a primary casting, a shaft secured upon said casting, a drive sleeve mounted upon said shaft, a belt wheel and a primary eccentric fixedly secured to said drive sleeve, an auxiliary eccentric loosely mounted upon said drive sleeve, and a gearing driven by said drive sleeve and positively connected to said auxiliary eccentric for operating said eccentric when said drive sleeve is rotated.

2. In an apparatus of the class described, the combination with a casting, of a shaft extending from said casting, a drive sleeve upon said shaft, a fixed and a loosely mounted eccentric on said drive sleeve, gear means connected to said loosely mounted eccentric and said drive sleeve for operating

said loosely mounted eccentric at a slower speed than said fixed eccentric, and a belt wheel fastened upon said drive sleeve.

3. In an apparatus of the class described, the combination of a casting, a shaft secured upon said casting, a drive sleeve upon said shaft, a belt wheel and a primary eccentric fixedly secured to said drive sleeve, an auxiliary eccentric loosely mounted upon said drive sleeve, a pinion fixedly secured to said drive sleeve, a gear supported by said casting and meshing with said pinion, and means connecting said auxiliary eccentric and gear whereby when said drive sleeve operates said pinion and gear, reciprocal movement will be imparted to said auxiliary eccentric.

4. In an apparatus of the class described, the combination of a stationary casting, an adjustable casting within said stationary casting, a shaft extending into said castings and mounted upon said stationary casting, a drive sleeve on said shaft and supported at its lower end upon said stationary casting, a belt wheel and a primary eccentric fixedly mounted upon said drive sleeve, an auxiliary eccentric on said drive sleeve, a pinion on said drive sleeve in engagement with said auxiliary eccentric, a gear mounted upon said adjustable casting and meshing with said pinion, and means extending into said auxiliary eccentric and detachably fastened to said gear whereby when said pinion and gear are operated by said drive sleeve, said auxiliary eccentric will be driven or operated at a slower speed than said primary eccentric.

5. In an apparatus of the class described, the combination of a primary casting, a shaft secured to said casting, a drive sleeve on said shaft, a belt wheel and a primary eccentric fixedly secured to said drive sleeve, a pinion on said drive sleeve, an auxiliary eccentric on said drive sleeve and bearing against the upper end of said pinion, said pinion being fixedly secured to said drive sleeve, a gear adjustably mounted upon said casting and meshing with said pinion, and means extending into said auxiliary eccentric and connected to said gear for operating the auxiliary eccentric when rotary movement is imparted to said pinion and gear through said belt wheel and drive sleeve.

6. In an apparatus of the class described, the combination of a primary casting, an auxiliary casting provided with a gear groove mounted within said primary casting, a shaft fastened at its lower end upon said primary casting, a drive sleeve mounted upon said shaft, a belt wheel and a primary eccentric keyed to said drive sleeve, an auxiliary eccentric loosely mounted upon said drive sleeve, a pinion fixedly secured to said drive sleeve against said auxiliary eccentric, a gear in said gear groove and meshing with said

pinion, a plate ring resting upon said gear, a locking ring fastening said plate ring and gear fixedly together, said plate ring provided with a roller lug extending into said auxiliary eccentric, and a tire-like sleeve on said roller lug.

7. In an apparatus of the class described, the combination of a primary casting, an auxiliary casting adjustably mounted on said primary casting, said auxiliary casting provided with a gear receiving groove, a shaft fastened in said primary casting, a drive sleeve on said shaft, a belt wheel and a primary eccentric keyed to said drive sleeve, an auxiliary eccentric loosely mounted on said drive sleeve, a pinion engaging said auxiliary eccentric and fixedly secured to said drive sleeve, a gear in said gear receiving groove, a ring plate resting against the upper edge of said gear, a locking ring between portions of said gear and said ring plate, fastening means on said ring plate and said locking ring for tightly holding the same together and locking said ring plate and gear against independent movement, said ring plate provided with an upstanding roller lug extending into said auxiliary eccentric, a ball bearing device on said roller lug, a tire-like sleeve on said roller lug, and a cover plate on said auxiliary eccentric over said roller lug, sleeve and ball bearing device.

8. In an apparatus of the class described, the combination of a primary casting, an auxiliary casting adjustably mounted on said primary casting, a shaft on said primary casting, a drive sleeve on said shaft, an eccentric loosely mounted on said sleeve, gear means mounted on said drive sleeve and said auxiliary casting, and means connecting said gear means to said eccentric whereby reciprocal movement is imparted to said eccentric through said gear means when said drive sleeve is rotated.

9. In an apparatus of the class described, the combination of a pair of castings, one mounted within the other, a shaft mounted within both of said castings, a drive sleeve on said shaft, gear means on one of said castings and connected to said drive sleeve, an eccentric loosely mounted on said drive sleeve, and means extending into said eccentric and connected to said gear means whereby when said drive sleeve is rotated, reciprocal movement will be imparted to said eccentric.

10. In an apparatus of the class described, the combination of a primary casting, said casting provided with a hub having a flanged upper end, a shaft screwed into said hub, a drive sleeve on said shaft and supported by said flanged upper end of the hub, a belt wheel and a primary eccentric keyed upon said drive sleeve, an auxiliary eccen-

tric loosely mounted upon said drive sleeve, a pinion on said drive sleeve and supported by said flanged upper end of the hub, said pinion engaging and supporting partly said auxiliary eccentric, a gear provided with means for partly supporting said auxiliary eccentric and imparting movement to said eccentric and said gear meshing with said pinion whereby the gears operate when rotary movement is imparted to the drive shaft and said pinion.

11. In an apparatus of the class described, the combination of a casting, a shaft carried by said casting, a drive sleeve on said shaft, a primary eccentric fixedly secured to said drive sleeve, an auxiliary eccentric loosely mounted upon said drive sleeve, means connected to said drive sleeve and to said auxiliary eccentric for operating the auxiliary eccentric at a slower speed than said drive sleeve and primary eccentric, and means whereby rotary movement may be imparted to said drive sleeve.

12. In an apparatus of the class described, the combination of a shaft, a drive sleeve loosely mounted on said shaft, a gearing fixedly connected to said drive sleeve, an eccentric loosely mounted on said drive sleeve, and means connecting said eccentric and gearing whereby when the drive sleeve and gearing is operated, movement will be imparted to said eccentric.

13. In an apparatus of the class described, the combination with a casting, a shaft secured upon said casting, of a drive sleeve on said shaft, said drive sleeve provided with a tapered portion, an eccentric mounted on said tapered portion of the drive sleeve, means for drawing said eccentric tightly upon said tapered portion, and a belt wheel fixedly secured to said drive sleeve.

14. In an apparatus of the class described, the combination with a casting, a shaft fastened upon said casting, of a tapered sleeve on said shaft, and a belt wheel and an eccentric adjustably mounted on said tapered sleeve.

15. In an apparatus of the class described, the combination with a casting, a shaft secured to said casting, of a drive sleeve provided with a tapered portion on said shaft, a belt wheel and an eccentric on the tapered portion of said sleeve, means on said belt wheel and said eccentric for drawing the same towards each other, a ring on said tapered portion of said drive sleeve, screw bolts on said ring and extending into said belt wheel, and a locking ring between said drive sleeve and said first mentioned ring.

In testimony whereof I hereunto affix my signature.

HERBERT H. ICE.
